CENTRIFUGAL POT CASTING

Edwin C. Young, Muskegon, Mich., assignor to
Sealed Power Corporation, Muskegon, Mich., a
corporation of Michigan

Application July 3, 1944, Serial No. 543,307

5 Claims. (Cl. 22—65)

This invention relates to centrifugal casting and is more specifically concerned with a mold for centrifugally casting sleeves or pots, as they are called, which after casting may be cut transversely to provide individual piston ring blanks, from each of which a piston ring is made.

Finished piston rings are parted at one side and normally are open at said parting greater or less distances, in accordance with the tension which the ring is to have when closed at the parting. When the ring is closed at the parting it takes circular forms at its outer and inner curved surfaces, as nearly perfect as it can be machined so as to bear against the inner walls of an internal combustion engine cylinder with equal pressure throughout its length. The initial casting for piston rings includes the finished casting plus an integral segment at one side which is cut from the casting, leaving the ring open, and when the ring is closed it takes the described circular form; therefore, the initial piston ring casting is of an out of round shape equivalent to the finished piston ring with a segment filling the gap or parting in it. Piston rings have been individually cast in such out of round form for many years; and also rings of a dimension such that they may be sawed to make generally two or more individual ring blanks have been cast in such out of round form, by still or static molding, that is, the pouring of molten metal into a stationary mold having the out of round shape cavities for receiving the metal.

With my invention a sleeve or pot is centrifugally cast in the desired out of round form and with walls of the same thickness or radial dimension. And it is a primary object and purpose of the present invention to provide a very practical, economical and certain mold construction, by means of which such centrifugal sleeve or pot casting may be expeditiously performed and perfect sleeves or pots obtained which may be cut transversely to provide a large number of individual ring blanks, each of which may be machined in accordance with accepted practice to obtain a piston ring for use in internal combustion engines, or at other places of use where rings or packing of this character are desirable. The piston ring thus produced has its metal of a substantially uniform homogeneous character throughout the body thereof.

An understanding of the invention may be had from the following description taken in connection with the accompanying drawings, in which,

Fig. 1 is a central vertical section through a mold in accordance with my invention and show-

ing the mold at the end of a casting operation therein, the section being substantially on the plane of line 1—1 of Fig. 4.

Fig. 2 is a horizontal section on the plane of line 2—2 of Fig. 1.

Fig. 3 is a central vertical section illustrating the flask and pattern used therewith, and the manner in which it is used for providing the outer green sand mold, and

Fig. 4 is a plan view of the mold shown in Fig. 1.

Like reference characters refer to like parts in the different figures of the drawings.

The flask 1 which may be of cylindrical form and of metal has a green sand mold 2 therewithin which preferably is obtained by inverting the flask, as in Fig. 3 and, placing it upon a bed plate 3 having a central opening and an exterior circular rim 4 within which the inverted edges of the flask 1 are received. A pattern 6 is provided and mounted on and extends above a movable stripper plate 5 through the opening in the bed plate, the upper end of which pattern has a cylindrical projection 7 with tapered sides as shown of reduced diameter. At the upper side of the bed plate 3 a frusto-conical member 8 as shown is secured by screws 9 through which the pattern 6 passes. Extending to one side from the member 8 is a bar 10 which extends to and through a notch to receive it in the lower end and at one side of the flask. The sand mold 2 is formed in the usual manner under proper tampering, ramming or squeezing, or in any of the ways in which the mold is made of the proper density, filling the space between the pattern and the flask and having an annular inwardly extending ledge 11 around the upper projection 7 on the pattern as shown, with an opening 12 with inclined sides left where the projection 7 was located. The pattern and plate 5 may be moved downwardly relative to the bed plate, flask and mold to strip the pattern from the mold and then the flask and mold removed from the plate 3 and the member 8 leaving the green sand mold 2 surrounding the central recess therein.

It is to be understood that the section 6 of the pattern between the projection 7 and the stripper plate 5 is of an outside shape corresponding to the outside out of round curvature desired in a piston ring casting. That is, the section 6 is not of a cylindrical form but is of the out of round shape and form like that of a circular pattern which has had a parting made at one side and a desired length of segment inserted therein. The flask 1 and the mold 2 therein, inverted after the mold has been formed, at their upper ends

will have a slot 13 in the flask at one side (Fig. 1) in which the pattern portion 10 was seated at its end in molding, and the mold 2 will have a slot 14 in alinement therewith.

The flask and mold are placed upon the upper side of the table 15 which is mounted for rotation about its vertical axis for centrifugal casting, the lower end portions of the flask when inverted being received within a surrounding rim 15a at the upper side of the table 15 as shown in Fig. 1. At the inner side of and at the lower portions of the rim 15a an annular groove 16 is cut extending downwardly and outwardly, from which radial passages 16a are made through to the outer side of the rim for the ready outward centrifugal expulsion of any loose sand which may be present at the upper side of the recessed portion of the table. In addition centrally of the table a cylindrical downwardly extending recess 17, the walls of which at the upper end portions are inclined outwardly and upwardly in conical form, is made from which lateral passages 18 extend for the same purpose of centrifugally throwing sand outward which may be in the recess 17. Also at its sides the table 15 is provided with vertical slots 19, the purpose of which will be later described.

Within the mold 2 a baked sand core 20 is positioned having a frusto-conical downwardly extending projection 21 which passes through the opening 12 in the mold and seats in the recess at 17. At its upper end the core is formed with an annular flange 22 shaped to be received in the mold 2 at the frusto-conical recess provided therein by the member 8 previously described. The intermediate portion of the core 20 likewise is not of a circular form, but is of an out of round form corresponding to the out of round shape of the inner walls of the mold 2 so that when properly located, the outer sides of the intermediate portion 20 of the core are spaced equally distant from the inner walls of the sand mold 2. In order that such proper positioning shall occur the flange 22 of the core is formed with a slot 23 for alinement with the slots 14 and 13 previously described, and such slot 23 is so located that when in such alinement the core will be properly positioned and be spaced at its outer surfaces equally from the inner surfaces of the mold.

The core 20 is provided with a central cylindrical opening 24 which extends downwardly the larger portion of the length of the core as shown. At the upper end of the core a second core 25 is positioned, being received in a recess made therein around the upper end of the cylindrical central opening 24, the core 25 being provided with an opening 26 preferably having inclined sides, the lower end of the opening 26 being of less diameter than the diameter of the opening 24.

With the core as thus described, properly positioned and located within the mold, a plate 27 of metal is placed over the upper ends of the flask, the mold 2 and the upper flanged portion 22 of the core 20, said plate having a central opening 28 through which the core at 25 extends, as shown. The plate 27 at its outer portions is provided with a downwardly extending ring 29 which passes around the upper end portions of the flask 1, and said ring 29 is provided at its edge portions with vertical slots 30. Headed bolts 31 are located in the slots 30 and 19 and nuts threaded into opposite ends of the bolts are tightened thereby clamping all of the parts in secured and firm relation to each other.

The pouring of metal is through the opening at 26 into the central downwardly extending opening at 24 within the core 20. Through a side of the core 20 horizontal passages are made for the molten iron to flow therefrom into the mold cavity between the inner walls of the mold 2 and the outer sides of the intermediate section of said core 20 as shown in Fig. 1. The table 15 being rotated at the requisite speed of rotation, the molten metal is forced outwardly by centrifugal action through said passages and fills the mold cavity to its upper end providing the sleeve or pot 32 from which narrow radial sections 33 extend inwardly through the passages in the core which have been mentioned, and the inner cylindrical opening 24 retains any excess of molten metal over that required to fill the mold cavities and may extend from the bottom of the opening 24 to the shoulder at the under side of the entrance or pouring core 25 as shown at 34. At the outer ends of the passages through which the molten metal passes to the mold cavity a thickened rib 35 may be provided, by a proper vertical longitudinal groove in the side of the core section 20 to serve as a marker on each individual ring casting or blank made by cutting or sawing the sleeve transversely, it being at such marker portion of the individual ring casting or blank that the parting segment is removed in the process of finishing the piston ring.

With this invention a mold having a proper green molding sand body is provided, associated with which is an interiorly positioned baked sand core, and with each of the molds as thus provided a centrifugal cast out of round pot or sleeve is expeditiously made. The transverse sawing or cutting of the sleeve or pot will produce from each sleeve a large number of piston ring blanks, each of which may be finished to make a cast piston ring. The green sand mold is rammed to its proper density and the quality and consistency of the green sand used is the same as has been used in previous still or static ring casting molds. The product obtained is one in which the metal is substantially homogeneous throughout, without variations in composition or in physical properties so that a uniformity of product is obtained in a practical economical manner.

Variations in detail of the mold structure may be resorted to without departing from the invention. For example, the upper projecting flange 22 of the core may extend to and seat against the flask 1 instead of the green sand mold 2, the inner side of the flask at its upper end being shaped to conform to the edges of the part 22. Also the core 25 may be made integral with the core 20 and not separate, without change in operation or function. Furthermore, instead of separated ports for the flow of the molten metal from the central recess 24 to the mold cavity between the core and the green sand mold a single port extending from the bottom of the central cavity 24 to or nearly to the upper end of the mold cavity may be provided. Likewise while preferably the mold at 2 will be of green sand and the core of baked sand, different materials than these can be used, as for example, in providing a permanent mold, using the materials which are normally used in permanent molds. All of these variations in detail are within the invention which is not avoided by such changes.

The invention is defined in the appended claims and is to be considered comprehensive

of all forms of structure coming within their scope.

I claim:

1. In centrifugal casting, a table adapted to be turned about a vertical axis, said table having a flask receiving recess at its upper side, a flask having its lower end received in said recess, a mold within said flask extending to the upper end thereof, said mold having a generally central larger vertical opening from its upper end nearly to its lower end, and a smaller central opening extending therefrom to the lower end of the mold, a core inserted lengthwise of said opening and having a projection at its lower end passing through the smaller opening in the lower end of the mold, said table in its upper side having a central recess receiving the lower end of said projection, said core at its outer sides above said lower smaller opening being spaced from the inner sides of the mold to provide an elongated sleeve-like recess, the upper end of the mold having an enlarged opening and the upper end of the core being enlarged to fit therein, said enlarged upper end of the core closing the upper end of said mold cavity, and said core having a central opening extending from its upper end downwardly therein to adjacent the lower end of said mold cavity with passage means for the flow of molten metal from said central opening to the cavity, as specified.

2. A construction as defined in claim 1, said mold cavity in horizontal cross section being of an out of round form like the outer of round shape of a piston ring casting, and the upper end of said mold and of said core having locating means thereon for properly locating the core and mold relative to each other to space the core at its sides thereof equal distances from the inner sides of the mold.

3. A construction as defined in claim 1, said core at its upper end having a second core with an opening therethrough for the pouring thereto of molten metal, said second core being

seated in the upper end portion of the first named core, and the opening through the second core at its lower end being of less cross sectional area than that of the downwardly extending opening in the first core.

4. A construction as defined in claim 1, a plate located over the upper ends of said flask, mold and core, and means for releasably securing the plate in position thereover, said plate having a central opening whereby molten iron may be poured into the central opening downwardly in said core.

5. In centrifugal casting a table adapted to be turned about a vertical axis, said table having a flask receiving recess at its upper side, a flask having its lower end received in said recess, a mold within the flask extending to the upper end thereof, said mold having a generally central larger vertical opening from its upper end and nearly to its lower end and a smaller central opening extending therefrom to the lower end of the mold, said larger vertical opening at its upper portion having an annular enlargement, a core inserted lengthwise of said opening having a projection at its lower end passing through the smaller opening in the lower end of the mold, said table at its upper side having a central recess receiving the lower end of said core, and said core at its upper end having a flange extending therefrom received in the annular enlargement of the upper end of said opening, said core between said flange and projection being spaced from the inner sides of the mold to provide an elongated sleeve-like cavity said core having a central opening extending from its upper end downwardly to adjacent the lower end of said mold cavity with passage means for the flow of molten metal from said central opening to the cavity, a plate located over the upper ends of the flask, mold and core and bearing thereagainst, and means detachably connecting said plate to the table.

EDWIN C. YOUNG.
